UNITED STATES PATENT OFFICE.

JOHN A. KIRKHAM, OF PORTLAND, OREGON.

DESIGN FOR A PICTURE-FRAME.

SPECIFICATION forming part of Design No. 34,887, dated August 6, 1901.

Application filed May 11, 1901. Serial No. 59,870. Term of patent 3½ years.

To all whom it may concern:

Be it known that I, JOHN A. KIRKHAM, a citizen of the United States, residing in Portland, in the county of Multnomah and State of Oregon, have invented and produced a new and original Design for a Picture-Frame, of which the following is a specification, reference being had to the accompanying drawings, forming a part thereof.

10 The leading feature of my design is a picture-frame representing on a flat surface a miniature Indian wigwam or tepee having an oval central opening through which the picture inserted in the frame is seen.

15 Figure 1 represents my picture-frame in elevation, and Fig. 2 is a horizontal section taken centrally through the oval opening for the picture.

The letters designate the parts referred to.

20 As shown in the drawings, the frame *a* has a conical appearance, tapering from the broad base to the top, from which project short ends of sticks *b*, crossing each other in resemblance of the poles of the wigwam or

tepee, for which the portion *a* represents the 25 covering. The surface of the frame is figured in simulation of the material from which the wigwam is constructed, and has also marked longitudinal and occasional oblique seams, as shown, to give the whole the appearance of 30 pieces of material fastened together. The central portion of the frame has an oval opening *c*, in which to set the picture, the thickness of the material from which the frame is made having the effect of giving depth to the 35 picture set in the frame.

Having thus described my invention, what I claim as new, and desire to secure by Letters Patent, is—

The design for a picture-frame, substantially as shown and described.

In testimony whereof I have hereunto affixed my signature, in the presence of two witness, this 30th day of April, 1901.

JOHN A. KIRKHAM.
